UNITED STATES PATENT OFFICE.

VIRGIL DRAPER, OF NORTH ATTLEBOROUGH, MASSACHUSETTS, ASSIGNOR
TO OSCAR M. DRAPER, OF SAME PLACE.

DESIGN FOR THE CROSS-BAR OF A CHAIN.

Specification forming part of Design No. 5,545, dated February 20, 1872.

To all whom it may concern:

Be it known that I, VIRGIL DRAPER, of North Attleborough, in the county of Bristol and State of Massachusetts, have invented a new and Improved Design for Cross-Bar for Ornamental Chain; and I hereby declare that the following specification, taken in connection with the drawings making a part of the same, is a full, clear, and exact description thereof.

The several figures, from 1 to 5 inclusive, exhibit in perspective and in cross-section the new design.

A in the several figures represents a bar, such as is commonly used as a means for securing a vest-chain to the button-hole. B is a fillet, placed midway between the extremities

of the bar A, and which is formed with an eye, a, for attaching the cross-bar to the chain. This fillet may be formed really or apparently of three members, b c d, which can be ornamented or left plain, as preferred.

What I claim as my invention, and desire to secure by Letters Patent, is—

The new design for a cross-bar for ornamental chains, which consists in forming the bar A with a three-member fillet, a, placed midway between the ends of the bar, substantially as described and shown in the drawings.

VIRGIL DRAPER.
